JOHN HOWARD BRUMBAUGH, OF CHICAGO, ILLINOIS, ASSIGNOR TO GENERAL FIRE EXTINGUISHER COMPANY, OF PROVIDENCE, RHODE ISLAND, A CORPORATION OF NEW YORK.

VALVE-CONTROLLING DEVICE.

1,396,808.

Specification of Letters Patent.

Patented Nov. 15, 1921.

Application filed June 22, 1920. Serial No. 390,861.

To all whom it may concern:

Be it known that I, JOHN HOWARD BRUMBAUGH, a citizen of the United States, residing at Chicago, in the county of Cook and State of Illinois, have invented certain new and useful Improvements in Valve-Controlling Devices, of which the following is a specification.

This invention relates to improvements in valve-controlling devices. More particularly it is herein illustrated as it may be applied in connection with dry pipe valves and the like. In one type of apparatus of this sort, known as an accelerator, there are provided two air chambers connected through a passage so restricted that although the pressure in them ordinarily is equalized by flow through the passage, yet it becomes unequal when one, consequent upon the opening of a sprinkler head, is subjected to a sudden change on too great a scale to be communicated with equal speed through the restricted connection. The resulting unbalanced pressure actuates a diaphragm whose function it is to throw open a discharge passage from one of the chambers, thus quickly actuating the dry pipe valve by any suitable method. Hitherto such passages have been maintained closed and leakage therethrough prevented, only by the weight and by the pressure of contained fluid upon a valve, such as a ball, closing the orifice of the passage. The present invention was devised to improve this part of the said apparatus by providing for a movable weight to be utilized first to hold the discharge passage valve closed, and next, upon the actuation of the diaphragm, to throw the said valve open against the pressure of the contained fluid. The invention may be applied to various other apparatus, and may be embodied in various forms within the scope of the appended claim. It is intended that the patent shall cover, by suitable expression in the appended claims, whatever features of patentable novelty exist in the invention disclosed.

In the accompanying drawing:

The single figure is a side elevation in medial section through an accelerator to which the invention is applied.

Referring to the drawing, 10 indicates a removable cover leading to the lower chamber 11 within a casing which also contains the upper chamber 12, these two being sepa-

rated, except as connected by a by-passage whose opening into the lower chamber is seen at 13. This communicates with the upper chamber through a disk 14 having a restricted opening which, protected by a screen 15 and suitably held in position by nuts 16, permits only slow passage of air between chambers 11 and 12. From chamber 12 another passage 17 leads to chamber 11 but is separated from it by a flexible diaphragm 18 which normally stands bulged toward chamber 12. Chamber 11 has a free connection 9 to the distributing pipes of the fire extinguisher system, not shown, which normally are filled with air under pressure, and has a discharge passage 26 to the dry pipe valve (not shown) where are suitable arrangements so that escape of air through the discharge passage causes actuation of this valve; and this discharge passage is normally closed by a valve body 25. It is the function of the diaphragm 18 to open the valve 25 under certain conditions. With this diaphragm is associated a plunger 19 on the chamber 11 side, suitably guided as at 20 in line to hit and knock over a weight 21 which stands up on an arm from its pivot 22, ready to be pushed over the pivot so as to fall down on the other side. The arm runs down beyond the pivot to a toe 23 which is set so that when swung around on the pivot 22 it traverses a path that makes it engage and lift the projecting end of a lever 24 which lifts valve 25 against the pressure of fluid contained in chamber 11. As illustrated, this consists of a ball resting down on the entrance to the discharge passage and having a stem and head 27 in position to be engaged and lifted by the lever 24 whenever the latter is swung upward around its fulcrum pivot 28. The parts thus far described were known prior to the present invention, the valve 25 as heretofore constructed being seated on the top of the discharge passage by its own weight, aided to a negligible degree by the weight of the lever 24, which is relatively light, and necessarily so because it has to be thrown up when the valve is opened. The principal reliance for keeping this valve tight has been the fluid pressure within chamber 11, acting upon it as upon a check valve.

The invention provides for holding this valve tightly seated, with a greater force, which force is automatically removed when

the valve is operated; and the agency exerting this force is the same element which causes the opening when the valve is operated viz: the weight 21, which may have a 5 pocket filled with lead 21' to enhance its weight. In its normal setting, ready to be operated when required, the weight 21 stands up above its pivot 22 and has its center of gravity somewhat to one side of that 10 pivot toward the valve 25, so that it tends to turn toward that valve, yet is so near the top of its swing that it is easily driven over the top by the plunger 19, its center of gravity swinging over the pivot 22 to fall down 15 on the other side. By this movement, superior force is applied, by the toe 23 against the lever 24, lifting the valve 25. According to the present invention, however, the weight 21 is so arranged, that when set ready and 20 waiting to be operated the weight 21 rests down on the end of lever 24 thus imposing its weight thereon to keep the valve 25 closed. The addition of a lug or projection 30 to the weight lever, on the side of its 25 fulcrum next to the weight and in position to engage the top side of the valve lever 24 imposes the weight 21 on the valve lever 24. As this projection 30 touches the lever 24 at its tip, which may be rather close to 30 the pivot 22 of the weight lever; and as the weight 21 may be relatively heavy and may have its center of gravity farther away from the pivot 22, and may be but loosely pivoted, a powerful compound leverage is produced 35 on the valve 25 tending to keep it tight against leakage. But the pressure through this leverage is immediately relieved when the plunger 19, pressing the weight 21 laterally, causes it to rise a little to the crest of 40 its arc, carrying the lug 30 away from the valve lever 24, and then to topple over on the other side, so that its toe 23 throws up the lever 24 and so opens the valve 25.

In its broader aspects the invention provides 45 means for holding the discharge valve 25 firmly seated with heavy pressure, additional to and considerably exceeding the fluid pressure upon it, until tripped; yet that valve is capable of being tripped by a 50 relatively light pressure automatically applied laterally to the upper part of the weight when the fluid pressure in chamber 11 becomes but little less than that in chamber 12; and when tripped is thrown open 55 with a strong force as said weight is shifted and falls. The apparatus is thus made more secure against leakage, and, for cases where this function is important, is made independent of the fluctuation of pressure on the 60 two sides of valve relative to each other, but can remain closed even though the direction of excess of fluid pressure shifts, until the prescribed condition for tripping occurs.

I claim as my invention:

65 1. The combination, with a valve body, of

a control lever separate therefrom, and means whereby it can engage the valve body in direction to close and in direction to open the valve; and a weight on said control lever; the whole being arranged to be set with 70 the weight supported near the crest of its swing by said engagement with the valve body, thereby holding the valve body closed, and adapted to be moved over the crest by lateral pressure and to fall on the other 75 side, thereby engaging the valve body to open the valve.

2. The combination, with a valve having an operating lever, of a control lever pivoted adjacent thereto and adapted to engage 80 the valve lever in direction to close the valve and in direction to open the valve; and a weight on the control lever; the whole being arranged to be set with the weight supported near the crest of its swing by said 85 engagement of the control lever with the valve lever, thereby holding the valve closed, in position where it is adapted to be moved over the crest by lateral pressure, and in falling on the other side to open the 90 valve by said other engagement.

3. The combination, with a valve normally closed by gravity and by fluid pressure, of a valve lever adapted to hold the valve body closed and to open it; and a 95 weighted control lever adapted to rest with its weight augmenting the said pressure to hold the valve closed, and adapted to move from said position by swinging on its fulcrum through a path which first relieves the 100 valve of said augmenting pressure and next causes the weight to fall with acceleration caused by gravity swinging the control lever, and then engages the valve lever to open the valve against said pressure.

4. The combination, in a valve actuating device, of a first and a second fluid chamber, connected by a restricted passage whereby the pressures between them may become balanced at a slow rate and unbalanced by rapid diminution of pressure in the first chamber, and separated by a flexible diaphragm adapted to be moved by an excess of pressure in one; a connection from the first chamber to exterior apparatus 110 wherein the fluid pressure may change; and a normally closed discharge passage from the first chamber whence the fluid therein may issue to actuate other apparatus; a valve body constituting said normal closure, 115 adapted to be seated on the discharge passage by the fluid pressure; a control lever having a weight eccentrically pivoted adjacent to the valve body and constituting a heavy arm of the lever; said lever having two other arms for engaging said valve body separately in opposite directions, one of them being adapted to support the weight from the valve body with the weight raised, and the other adapted to lift the 120 125 130

valve body by momentum of the falling weight on the other side of its pivot; and means whereby said diaphragm pushes the weight to the other side of its pivot upon the occurrence of an excess of pressure in the second chamber.

5. The combination in a valve actuating device of a first and a second fluid chamber, connected by a restricted passage 10 whereby the pressures between them may become balanced at a slow rate and unbalanced by rapid diminution of pressure in the first chamber, and separated by a flexible diaphragm adapted to be moved by an excess of pressure in one; a connection from 15 the first chamber to exterior apparatus wherein the fluid pressure may change, and a normally closed discharge passage from the first chamber whence the fluid therein 20 may issue to actuate other apparatus; said discharge passage having within the first

chamber an orifice opening upward; a valve body closing it; a valve lever adapted to lift the valve body and also to maintain it closed; a control lever pivoted adjacent and 25 normally standing up on its pivot and having a part adapted to engage the valve lever to press it down when standing up, and having a weight thereby held upstanding, pressing down on the valve lever, and in position 30 to be overturned; said upstanding lever also having an arm adapted to engage the valve lever to lift it when swung around by the overturning of the weight; and means controlled by said diaphragm whereby the rising of excess of pressure in the second chamber lifts the weight, thereby releasing the valve and then overturns it, thereby lifting the valve.

Signed at Chicago, this 20th day of May, 40
1920.

JOHN HOWARD BRUMBAUGH.
